UNITED STATES PATENT OFFICE.

WALTER C. CUNNINGHAM, OF ST. PAUL, MINNESOTA.

DESIGN FOR A TOBACCO-PIPE MEMBER.

SPECIFICATION forming part of Design No. 30,660, dated May 2, 1899.

Application filed March 24, 1899. Serial No. 710,369. Term of patent 7 years.

To all whom it may concern:

Be it known that I, WALTER C. CUNNINGHAM, a citizen of the United States, residing at St. Paul, in the county of Ramsey and State of Minnesota, have produced and invented a new and original Design for Tobacco-Pipe Members, of which the following is a specification.

This invention relates to tobacco-pipe members; and the design thereof is illustrated in the accompanying drawing, in which the figure is a perspective view of the design.

The leading feature of my design is the outline of the tobacco-pipe member in the form herein shown and described. The main or body portion is of a semi-egg shape or in the form of one-half of an oblate spheroid divided longitudinally and truncated at one end. Branching from the body portion at its rounded end and integral therewith is a slightly-tapering semicylindrical projection flat on one side, the flat side coincident with the flat side of the main body portion. Within the flat side of the body portion is a circular cavity, with an opening in one side leading out through the truncated end of the body portion. In the bottom of the circular cavity is a slightly-tapered depression or continuation of the circular cavity opening outward

through the truncated end of the body portion. The interior of the circular cavity is formed into angular parallel grooves running around the interior of the circular cavity. In the center of the flat side of the semicylindrical projection is a semicircular groove opening into the circular cavity at one end and out through the end of the projection at the other end.

Referring to the drawing by letter, A designates the semi-egg-shaped body portion; B, the tapered semicylindrical projection; D, the circular cavity; E, the depression within the circular cavity; *a*, the angular grooves within the circular cavity, and *b* the semicircular groove within the flat side of the semicylindrical tapered projection.

Having thus described my invention, what I claim as new, and desire to secure by Letters Patent, is—

The design for a tobacco-pipe member, as herein shown and described.

In testimony whereof I have hereunto set my hand in the presence of two subscribing witnesses.

WALTER C. CUNNINGHAM.

In presence of—

LEWIS D. MANN,
C. N. WOODWARD.
